UNITED STATES PATENT OFFICE.

DAVID LEMOINE AND GEORGE P. FOURNIER, OF WHITINSVILLE, MASSACHUSETTS.

BOBBIN-DRIVING DEVICE FOR SPINDLES.

1,294,494.

Specification of Letters Patent. Patented Feb. 13, 1919.

Application filed June 15, 1918. Serial No. 240,230.

To all whom it may concern:

Be it known that we, DAVID LEMOINE and GEORGE P. FOURNIER, citizens of the United States, both residing at Whitinsville, in the 5 county of Worcester and State of Massachusetts, have invented a new and useful Bobbin-Driving Device for Spindles, of which the following is a specification.

This invention relates to a device for centering and driving a bobbin on a rotatable spindle such as is used in spinning or twisting operations.

A rigid bobbin seat has been found impractical owing to unavoidable variations 15 in the diameter of the holes in the bobbins, due to defects in manufacture or changes in condition while in use. Different forms of adjustable bobbin engaging and driving devices have been heretofore used, presenting 20 certain elements of utility, but so far as we are advised no one of these devices has given entire satisfaction, particularly in the matter of accumulating lint and waste.

It is the general object of our invention 25 to improve this type of spindle driving device, providing a driving device by which any bobbin within the range of adjustment of the device will be both accurately centered and positively rotated.

With this general object in view we provide a plurality of bobbin engaging arms 30 separately mounted on the upper end of the spindle whirl, and important features of our invention relate to the form and construction of these arms. Other important 35 features relate to the manner of supporting the arms upon the whirl; to the means for forcing the arms yieldingly outward to engage the bobbin; and to the means for limiting both outward and upward movement 40 of said arms relative to the spindle blade.

Other features of our invention relate to arrangements and combinations of parts hereinafter described and more particularly 45 pointed out in the appended claims.

A preferred form of our invention is shown in the drawings, in which—

Figure 1 is a sectional elevation of a spindle embodying our improvements;

Fig. 2 is a similar view but showing the parts in driving engagement with a bobbin;

Fig. 3 is a transverse sectional view taken along the line 3—3 in Fig. 1, and

Fig. 4 is a perspective view of one of 55 the driving arms.

We have shown a spindle blade 10 and

whirl 11 essentially of the usual form. A plurality of bobbin engaging arms 12 are supported upon the upper end of the whirl 11. Each arm 12 is provided at its lower 60 end with an outwardly and downwardly extending flange 13 adapted to be seated in an annular recess 14 formed in the upper end of the whirl 11. The recess 14 is preferably substantially semi-circular in cross 65 section and closely corresponds to the section of the flange 13.

A portion 15 of each arm 12 projects slightly upward from the upper side of the flange 13 and engages the under side of a 70 flanged cap 16 having a driving fit upon the outside of the whirl 11. The inner edge of the cap 16 engages the outer face of each arm 12 when the arm is in the position shown in Fig. 1, and thus limits outward 75 movement thereof.

A coil spring 17 is seated in a circular groove 18 in the upper face of the whirl 11, said spring engaging the arms 12 as shown in Fig. 1, and yieldingly moving 80 them to outer or inoperative position. The arms 12 may be provided with short depending projections 19 adapted to center the spring and to hold the arms and spring in operative relation. Upward pressure of 85 the spring adjacent the projections 19 will rock each arm about its bearing in the recess 14 and will swing the upper end of the arm outwardly until the arm engages the cap 16. Driving pins 20 separate the 90 arms 12 and constitute means for positively rotating the arms with the whirl.

When a bobbin is placed on the spindle the arms move inward, as shown in Fig. 2, slightly compressing the spring 17. The 95 tension of the spring 17 is then sufficient to positively drive the bobbin with the spindle. The provision of the opposed engaging portions 13 and 15 permits each arm to move freely about its bearing in the recess 14, 100 while at the same time preventing movement of the arm longitudinally of the spindle.

In their inward and outward movements, the arms 12 swing about their bearings in 105 the recess 14 and are thus continuously and accurately centered in every position. It will also be noted that the arms 12, the cap 16, and the spring 17 are all supported entirely free of the blade 10. The blade may 110 therefore be removed from the whirl 11 without affecting the spindle driving de-

vice, and moreover any slight bend in the blade between the whirl and the tip will not cause the bobbin to run off center. As spindle blades are commonly straightened so that the tip and the whirl will run true regardless of any slight bend between these two points, this support of the lower end of the bobbin independently of the blade is of considerable importance.

10 It will also be seen that the arms 12 are entirely free and unobstructed above the cap 16, thus permitting cutting and removal of any waste or lint found on the spindle. At the same time the spring 17 is fully protected from injury or displacement.

Having thus described our invention, it will be evident that changes and modifications can be made therein by those skilled in the art without departing from the spirit and scope thereof as set forth in the claims, and we do not wish to be otherwise limited to the details herein disclosed, but what we claim is—

25 1. A spindle having, in combination, a blade, a whirl with an annular recess and a concentric groove in its upper end, a plurality of arms surrounding said blade and each seated at its lower end in said recess, means to prevent displacement of said arms, and a spring seated in said groove and yieldingly engaging said arms to move them away from said blade.

30 2. A spindle having, in combination, a blade, a whirl having an annular groove of 35 substantially semi-circular cross section

formed in its upper end, a plurality of bobbin-engaging arms each having an outwardly and downwardly projecting flange rounded at its lower end to fit said annular groove, a cap fitting said whirl and limiting outward movement of said arms, and means to move said arms yieldingly outwardly.

3. A spindle having, in combination, a blade, a whirl mounted thereon and having an annular groove formed in its upper end, a plurality of bobbin-engaging arms each having an outwardly and downwardly projecting flange shaped at its lower end to fit said annular groove, a cap fitting said whirl and limiting upward and outward movement of said arms, and means inclosed between said cap and whirl effective to move said arms yieldingly outwardly.

4. A spindle having, in combination, a blade, a whirl mounted thereon, a plurality of upwardly extending arms having their lower ends seated on the upper surface of said whirl, a cap fitting said whirl and limiting outward and upward movement of said arms, and a spring seated on said whirl below said arms and cap and engaging said arms to force said arms yieldingly away from said blade and against said cap, said arms, cap, and spring being supported by said whirl independently of said blade.

In testimony whereof we have hereunto affixed our signatures.

DAVID LEMOINE.
GEORGE P. FOURNIER.
